UNITED STATES PATENT OFFICE.

THOMAS M. HOUSE, OF RICHMOND, VIRGINIA, ASSIGNOR TO HOUSE HARDWARE COMPANY, OF RICHMOND, VIRGINIA, A CORPORATION OF VIRGINIA.

CUTTER-MOUNTING FOR PAPER-ROLL HOLDERS.

1,333,022.

Specification of Letters Patent.

Patented Mar. 9, 1920.

Application filed October 11, 1919. Serial No. 330,001.

To all whom it may concern:

Be it known that I, THOMAS M. HOUSE, a citizen of the United States, residing at Richmond, in the county of Henrico and State of Virginia, have invented certain new and useful Improvements in Cutter-Mountings for Paper-Roll Holders, of which the following is a specification, reference being had to the accompanying drawings.

This invention relates to holders for holding rolls of papers, and particularly to certain improvements in the paper roll holder illustrated and claimed in the patent granted to me on August 26, 1919, No. 1,314,267.

In the paper roll holder illustrated in this patent, there is shown a cutting blade which extends parallel to the paper roll and which is movable away from the axis of the paper roll spindle but which is resiliently urged toward the paper roll spindle so as to bear at all times against the face of the paper carried by said roll. The cutting blade in this patent is rigidly mounted upon supporting arms and as a consequence, the blade takes different angular positions relative to the paper as the diameter of the paper roll decreases, in other words when the paper roll is of full size the blade extends practically flat against the periphery of the paper roll, then as the paper is removed from the roll and the blade moves inward, it gradually increases its angle to the paper. I have found in actual practice that blades do not cut as well when they are disposed flat against the roll of paper as they do when the blade is disposed at an angle thereto, and the general object of this present invention is to improve upon the mounting for the cutting blade and upon the cutting blade itself so that the cutting blade will at all times have the same angular position relative to the periphery of the paper roll without regard to whether the roll of paper is relatively large or relatively small in diameter.

A further object is to pivotally mount the blade upon the supporting arms and provide the blade with a portion which bears against the paper and acts to hold the blade in correct relation to the paper without regard to the movement of the supporting arms.

Still another object is to so construct the

paper roll holder that the blade with its arms may be readily released and detached from engagement with the base of the machine and from the roll holding spindle when it is desired to place a new roll of paper upon the spindle or remove the central core of an old roll therefrom.

Other objects will appear in the course of the following description.

My invention is illustrated in the accompanying drawings, wherein:

Figure 1 is a side elevation of a paper roll holder with my improved blade mounting thereon;

Fig. 2 is a section taken just above the arm 21 looking down on the roll;

Fig. 3 is a fragmentary perspective view of the connection between the arms 17 and 21;

Fig. 4 is a sectional perspective view of the cutting blade;

Fig. 5 is a sectional perspective view of the rivet;

Fig. 6 is a fragmentary top plan view showing the means for holding the upper end of the roll in place on the spindle.

As my paper roll holder is fully illustrated in the patent above referred to, it is only necessary to say that the paper roll holder comprises a base 10 which is preferably made of cast metal and formed with an upstanding hub 12. The margin of the base is downwardly turned or flanged, as at 13, and the base is provided with apertures for holding screws.

Extending upward from the base is a spindle 14 which is detachably connected to the base. The roll of paper A rests upon a plate 15 which supports the lower centering collar for the paper (not shown).

For the purpose of supporting the cutting blade by which the paper is cut, I mount upon the boss 16 on the base 10 the lever 17 which is pivoted, at 18, and which is drawn in one direction by a contractile spring 19. This lever is formed at its outer end with a vertical socket 20. The arm 21 has its outer extremity angularly bent, as at 22, and inserted in this socket, and this arm 22 is connected to the cutting blade 23 in a manner which will be later stated. At its upper end, the blade 23 is likewise connected in a manner which will be later stated to an arm 24 which is pivoted upon an arm 26. The upper end of the spindle

14 is reduced in thickness, as at 27, and the extremity of the arm 26 is formed with a notch snugly fitting this reduced portion. The reduced portion 27 of the spindle is likewise formed with a recess 28 in its end and a latch 29 pivoted upon this arm 26 is adapted to engage in said recess to lock the arm 26 to the spindle. A spring 30 draws the extremity of the latch into the notch 28 and this spring is connected to the arm 24 so as to urge this arm inward. All of these parts are fully illustrated and described in my patent above referred to, except that in the patent above referred to, the angular 10 end 22 of the arm 21 is not disposed in the socket 20 in the lever 17. It will be seen that the spring 19 and 30 act to urge the arms 24 and 21 toward the paper roll and resiliently force the blade 23 against the 15 paper roll.

The blade 23 is approximately U-shaped. The blade is made of sheet metal and is formed to provide the inner side wall 31 and the outer side wall 32. The edge of the outer side wall is deflected outward, as at 33, this wall 33 forming the blade proper against which the paper is cut. The wall 31 is outwardly turned along its margin, as at 34, so as to bear yieldingly against the 20 periphery of the paper roll A. The side wall 31 at its upper and lower ends is formed with relatively large perforations 35 through which the arms 21 and 24 extend. These arms 21 and 24 are relatively 25 small in comparison with the slots 35. Each of these arms at its end within the U-shaped cutter 23 is provided with a rivet, the shank 36 of which extends through a perforation in the outer face of the member 23 and is provided with the usual head, the inner end of this shank being provided with a triangular head 37 which bears against and forms a fulcrum for the cutter 23. This rivet, it will be understood, extends 30 at all times from the arms 21 and 24 at the same angle, but the cutter may rock upon the apex of the triangular head 37 in a manner which will be plain from the drawings. Under these circumstances, it will be seen that the cutter 23 bears at all times against the periphery of the paper roll at two points, namely at the edge of the deflected cutting margin 33 and the edge of the rounded portion 34. Thus, no matter whether the paper 35 roll be large or small, the cutting edge 33 will always be disposed at exactly the same angle to the paper and the difference in curvature of the periphery of the roll, due to the differences in diameter of the roll, will 40 simply act to shift the cutter 23 upon its pivots. The part 34 constitutes means, it will be seen, for holding the cutting blade formed by the wall 32 in a proper relation at all times to the surface of the paper and 45 the arms 21 and 24 form swinging supports

for the cutter which are resiliently urged toward the spindle of the paper roll.

When the paper roll has been exhausted and it is desired to place a new paper roll in place on the holder, the latch 29 is released from its engagement with the upper end of the spindle and then the cutter 23 may be lifted, which will detach the arm 21 from its engagement with the socket 20. A new roll of paper may then be put in place. 75 The arm 21 can engage with the socket 20 and then the arm 26 engaged with the upper end of the spindle 14 and locked in place by the latch 29.

I claim:

1. A paper roll holder including in combination a roll supporting spindle, a base therefor, a lever mounted upon the base and having a socket at one end extending upward from the lever, a blade extending parallel to the spindle, an arm engaged with the lower end of the blade and at its free end being angularly bent to fit in said socket and for movement with the lever, an arm connected to the upper end of the blade, means for pivotally supporting said arm detachably engaged with the upper end of the spindle, and springs acting to urge said blade toward the spindle. 80

2. A paper roll holder including a roll supporting spindle, cutter supporting arms coacting therewith and resiliently urged toward the spindle, and a cutter extending parallel to the spindle and rockingly engaged with said arms for rocking movement in a plane parallel to the planes of movement of said arms, the cutter having a part carried thereby and movable therewith extending at an angle to the cutter and adapted to bear against the roll of paper coincidently with the cutter to thereby support said cutter with its cutting edge at all times at the same angle to the outer surface of the roll. 95

3. A paper roll holder comprising a roll supporting spindle, a cutter extending parallel to the spindle, arms operatively supported to coact with the cutter and resiliently urged toward and from the spindle, a connection between said arms and the blade permitting the blade to rock in a plane parallel to the planes of movement of said arms, and means engaging the paper on the roll supporting spindle and acting to support said cutter with its cutting edge at all times against and at the same angle to the outer surface of the roll. 110

4. A paper roll holder comprising a roll supporting spindle, a cutter extending parallel to the spindle, arms operatively supported to coact with the cutter and yieldingly urged toward and from the spindle, a connection between said arms and the blade permitting the blade to rock in a plane parallel to the planes of movement of said 115 arms. 125

- arms, and means spaced from the cutting edge of the cutter and carried by the cutter, engaging the paper roll and supporting the cutter with its cutting edge at all times 5 against and at the same angle to the outer face of the paper roll, the point of connection of the cutter to said arms being disposed between said means and the cutting edge of the blade.
- 10 5. A paper roll holder including a roll supporting spindle, a blade extending parallel to the spindle, said blade being approximately U-shaped in cross section, both edges of said U-shaped blade engaging 15 against the surface of the roll, and means supporting said blade and yieldingly urging it toward the roll, said means permitting the blade to rock in a plane parallel to the planes of movement of said supporting 20 means.
6. A paper roll holder comprising a paper roll supporting spindle, a cutter extending parallel to the spindle, said cutter being approximately U-shaped in cross section, a 25 concave face of the cutter being disposed toward the spindle whereby the two edges of the cutter will lie against the surface of the roll, supporting arms operatively pivoted for parallel movement toward and from the 30 spindle, one side wall of the cutter being perforated and the adjacent extremities of the supporting arms extending through said perforations, and members attached to the extremities of said arms and extending at 35 right angles thereto and through the U-shaped cutter to the exterior face thereof, said members being formed with triangular heads at their outer ends against the apices of which said cutters bear and rock.
7. A paper roll holder comprising a paper roll supporting spindle, a cutter extending parallel to the spindle, said cutter being approximately U-shaped in cross section, a concave face of the cutter being disposed toward the spindle whereby the two edges 40 of the cutter will lie against the surface of the roll, supporting arms operatively pivoted for parallel movement toward and from the spindle, one side wall of the cutter being perforated and the adjacent extremities of 45 the supporting arms extending through said perforations, and rivets attached to the ends of said arms and extending at right angles therefrom through the cutter and provided at their outer ends with triangular heads 50 forming fulcrums for the cutter to rock on.
8. A paper roll holder including a roll supporting spindle, a blade extending parallel to the spindle and approximately 55 U-shaped in cross section, one wall of said U-shaped blade being deflected to form a cutting edge, the other wall being rounded at its margins, the cutting edge of this rounded margin bearing at all times against the surface of the roll on the spindle, and means supporting the blade, yieldingly urging it against the surface of the paper roll, and permitting said blade to rock transversely of its length.

In testimony whereof I hereunto affix my 70 signature.

THOMAS M. HOUSE.
